UNITED STATES PATENT OFFICE

153,536

DESIGN FOR A GLASS PLATE FOR
LIGHTING FIXTURES

Robert G. McPhail, Newark, Ohio, assignor to
Holophane Company, Inc., New York, N. Y., a
corporation of Delaware

Application May 15, 1948, Serial No. 146,392

Term of patent 14 years

(Cl. D48—16)

To all whom it may concern:

Be it known that I, Robert G. McPhail, a citizen of the United States of America and a resident of Newark, county of Licking, State of Ohio, have invented a new, original, and ornamental Design for Glass Plate For Lighting Fixtures, of which the following is a specification, reference being had to the accompanying drawings, forming a part thereof.

In these drawings:

Figure 1 is an inverted plan view of a glass plate for lighting fixtures, showing my new design;

Figure 2 is a side elevational view of the plate;

Figures 3 and 4 are end elevational views taken from the right and left, respectively, of Figure 1; and

Figure 5 is a fragmentary section on the line 5—5 of Fig. 1 at an enlarged scale.

I claim:

The ornamental design for a glass plate for lighting fixtures, as shown.

ROBERT G. MCPHAIL.
